US0D1073917S

(12) **United States Design Patent** (10) Patent No.: **US D1,073,917 S**
(45) Date of Patent: ** May 6, 2025

(54) **FIN SHAPED AIR HEATER**

(71) Applicant: **Kogaku Technology Inc.**, Miaoli County (TW)

(72) Inventors: **Yueh-Lin Chiang**, Miaoli County (TW); **Hsin-Jan Pai**, Miaoli County (TW); **Ying-Feng Lee**, Miaoli County (TW); **Ling-Chiao Huang**, Miaoli County (TW)

(73) Assignee: **Kogaku Technology Inc.**, Miaoli County (TW)

(**) Term: **15 Years**

(21) Appl. No.: **29/862,902**

(22) Filed: **Dec. 13, 2022**

(51) LOC (15) Cl. **23-03**

(52) U.S. Cl.

USPC **D23/417**

(58) **Field of Classification Search**

USPC D23/341, 386, 415, 417

CPC H01L 21/67017

(57) **CLAIM**

The ornamental design for a fin shaped air heater, as shown and described.

DESCRIPTION

FIG. 1 is a perspective view from the top of the fin shaped air heater.

FIG. 2 is a front view of the fin shaped air heater.

FIG. 3 is a left side view of the fin shaped air heater.

FIG. 4 is a right side view of the fin shaped air heater.

FIG. 5 is a rear view of the fin shaped air heater.

FIG. 6 is a top view of the fin shaped air heater; and,

FIG. 7 is a bottom view of the fin shaped air heater.

1 Claim, 4 Drawing Sheets
